CLAIM

We claim, the ornamental design for a tool connector, as shown and described.

DESCRIPTION

FIG. 1 is a front top perspective view of the design;
FIG. 2 is a front bottom perspective view of the design of FIG. 1;
FIG. 3 is a front view of the design of FIG. 1, the rear view being a mirror image thereof;
FIG. 4 is a side view of the design of FIG. 1, the opposite side being a mirror image thereof;
FIG. 5 is a top view of the design of FIG. 1; and,
FIG. 6 is a bottom view of the design of FIG. 1.
The broken lines shown in FIGS. 1, 2, 5-8, 11 and 12 is illustrating an unclaimed portion of the tool connector and form no part of the claimed design.
